UNITED STATES PATENT OFFICE

164,698

GASOLINE FILTER

Verner P. Mathews, near Dayton, Ohio, assignor
to General Motors Corporation, Detroit, Mich.,
a corporation of Delaware

Application October 1, 1949, Serial No. 5,249

Term of patent 14 years

(Cl. D46—1)

To all whom it may concern:

Be it known that I, Verner P. Mathews, a citizen of the United States, residing near Dayton, in the county of Montgomery, and State of Ohio, have invented a new, original, and ornamental Design for a Gasoline Filter, of which the following is a specification, reference being had to the accompanying drawing, forming a part hereof.

In the drawing:

Fig. 1 is a view, in perspective, of one side of a gasoline filter embodying my new design.

Fig. 2 is a view, in perspective, of the other side of the gasoline filter.

Fig. 3 is an edge view of the gasoline filter.

I claim:

The ornamental design for a gasoline filter, as shown.

VERNER P. MATHEWS.
